[57] CLAIM

The ornamental design for a console air cleaner, as shown and described.

DESCRIPTION

FIG. 1 is a front perspective view of a console air cleaner showing our design.

FIG. 2 is a front elevational view of the air cleaner shown in FIG. 1.

FIG. 3 is a rear elevational view of the air cleaner shown in FIG. 1.

FIG. 4 is a left side elevational view of the air cleaner shown in FIG. 1.

FIG. 5 is a right side elevational view of the air cleaner shown in FIG. 1; and,

FIG. 6 is a top plan view of the air cleaner shown in FIG. 1. The bottom of the design is plain and unornamented.
